[57] CLAIM

The ornamental design for a duffle satchel, substantially as shown and described.

DESCRIPTION

FIG. 1 is a right front perspective view of a duffle
satchel, showing my new design;

FIG. 2 is a front elevational view thereof;

FIG. 3 is a right rear perspective view thereof;

FIG. 4 is a left front perspective view thereof;

FIG. 5 is a top plan view thereof;

FIG. 6 is a bottom plan view thereof; and

FIG. 7 is a front perspective view of the duffle satchel with the carrying strap in position for use as a duffle bag.

FIG. 1

FIG. 2

FIG. 3

FIG. 5
